(57) **CLAIM**

The ornamental design for a sitting-drop microwell plate for crystallization, as shown and described.

DESCRIPTION

FIG. 1 is a perspective view of the top and sides of the claimed invention.

FIG. 2 is a top view thereof.

FIG. 3 is a right side view thereof.

FIG. 4 is rear view thereof.

FIG. 5 is a front view thereof.

FIG. 6 is a bottom view showing the shape of the bottom. The bottom surface forms no part of the claimed design; and,

FIG. 7 is section of a single well indicated in FIG. 2.

The broken lines in FIG. 2 indicate the well that is shown in cross-section in FIG. 7 and line 7—7 indicates the line along which the cross-section is taken. The other broken lines in the figure views indicate boundaries or regions that form no part of the claimed design.
